UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,138,138.

Specification of Letters Patent.

Patented May 4, 1915.

Application filed April 11, 1914. Serial No. 831,288.

To all whom it may concern:

Be it known that I, JOHN F. O'CONNOR, a citizen of the United States, residing at Chicago, in the county of Cook and State of Illinois, have invented a certain new and useful Improvement in Draft-Riggings for Railway-Cars, of which the following is a full, clear, concise, and exact description, reference being had to the accompanying drawings, forming a part of this specification.

My invention relates to improvements in draft rigging for railway cars.

The object of my invention is, to provide a draft rigging of cheap and simple construction, and effective operation.

In the drawings forming a part of this specification, Figure 1 is a side elevation, partly in vertical longitudinal section, of a draft rigging embodying my invention; Fig. 2 is a horizontal section taken on line 2—2 of Fig. 1; Fig. 3 is a cross section taken on line 3—3 of Fig. 1; Fig. 4 is a central vertical longitudinal section, and showing the position of the parts in buff.

Referring to the drawings, the numerals 5—5 represent draft sills or parts of the car frame to which the draft rigging is applied.

Mounted between the draft members is a draw-bar 6, the rear end thereof only being shown in the drawing; a draft yoke 7; compression resisting members 8; front and rear followers 9 and 10, respectively; a stationary key 11; a coupler key 12; and stop members 13—13. The stationary key 11 is preferably a broad flat key passing transversely between the draft members 5—5, and mounted at its ends within the slots 14—14 in the draft members, the said key being preferably secured against accidental displacement by cotters 15—15 passed through its ends. The key 11 passes through the yoke 7 in the transverse slots 16 provided in the limbs 17—17 of the yoke, the said slots being longitudinally rearwardly extended to permit sliding movement of the yoke upon the key 11.

The limbs 17—17 of the yoke 7 are provided near their forward ends with the transverse slots 18—18 for the passage of the coupler key 12 therethrough, the said

coupler key passing through the usual transverse slot 19 in the draw-bar and through the slots 20—20 in adjacent portions of the draft members 5. The slots 20—20 in the draft members are suitably extended longitudinally to permit the movement of the key 12 therein in both forward and rearward movement of the draw-bar. The slots 18—18 in the draft yoke are sufficiently rearwardly extended to permit the coupler key 12 to slidingly move rearwardly therein on rearward movement of the draw-bar 6 in buffing action of the draft rigging.

The stop members 13—13 are forwardly provided with the stop-shoulders 21—21, against which the front follower 9 is held against forward movement in pulling action of the draft rigging, and with rear stop-shoulders 22—22 against which the rear follower 10 is held against rearward movement in buffing action of the draft rigging.

The compression resisting members 8 are mounted between the two followers, the said compression resisting members preferably comprising springs, which preferably are mounted in vertical twin arrangement. In such arrangement the springs are in two sets, the upper set 23 being mounted above the stationary key 11, and the lower set 24 being mounted below the stationary key 11. Each set preferably comprises an outer spring 25 and an inner spring 26 nested therein. The followers are each preferably provided with upper and lower bosses 27 and 28, respectively, on their inner opposed faces, about which the inner springs are seated at their ends, the said bosses serving to support the springs and prevent the accidental downward displacement thereof. The springs, particularly the upper set thereof, also prevent the accidental downward displacement of the followers by reason of the intervention between the upper and lower sets of springs of the stationary key 11.

In the form of my invention illustrated in the drawings, the stop members 13 are formed by upper and lower members 29 and 30, respectively, spaced apart to permit the passage of the draft yoke 7 between them. The members 29 and 30 are each preferably

of a general channel shape, the flanges 31 of the upper member 29 being up-turned, and the flanges 31 of the lower member 30 being down-turned. The said members 29 and 30 are each secured to the draft members by suitable means, preferably rivets 32—32 passing through the respective flanges of the said members and through the adjacent draft members. The members 29 and 30 are each provided with an opening 33 intermediate the ends of the member, the said openings registering with each other, and the compression resisting members and followers being received therein. Each of said openings is of suitable width to permit the mounting of a set of springs between the sides thereof, as most clearly shown in Fig. 3 of the drawings. The web 34 at the forward end of each member 29 and 30 forms the front stop-shoulders 21, and the web 35 at the rear end of said members forms the rear stop-shoulders 22—22. For the sake of economy, it is practical to use the portion cut from each of the members 29 and 30 to form the openings 33 for the followers 9 and 10. In preferable construction, the slots 16 in the limbs of the draft yoke are of such length that the forward ends 35 of said slots are in engagement against the front edge of the stationary key 11 when the rear follower 10 is in engagement against the rear stop-shoulders 22, and when the rear follower is also in engagement against the rear connecting portion 36 of the yoke 7. On forward movement of the draw-bar, the coupler key 12 engages against the forward ends of the slots 18 in the limbs of the draft yoke 7, the draft yoke is drawn forwardly upon the stationary key 11, the said draft yoke forwardly actuating the rear follower 10, and compressing the compression resisting members against the front follower, which is stopped against the front stop-shoulders 21. It will be observed that should a breakage of the compression resisting members occur by any chance, the car will be drawn by the yoke through its connection with the stationary key,—and should not only the compression resisting members fail, but should the yoke also fail, then the car may be drawn by an engagement of the coupler key within the slots 20 in the draft members. The stationary key 11 may also serve as a stop to limit the forward movement of the rear follower in pulling action of the draft rigging. On rearward movement of the draw-bar, the coupler key 12 slides rearwardly within the slots 18 in the limbs of the draft yoke and in the slots 20 in the draft members, the rear of the draw-bar engaging directly against the front follower 9, which moves rearwardly against the compression resisting members, which are held against rearward

movement by the rear follower 10, the rear follower being stopped by the rear stop-shoulders 22 and also by the yoke, which is held against rearward movement by the stationary key 11.

The position of the parts when under full buff is illustrated in Fig. 4 of the drawings.

I claim:—

1. In a draft rigging for railway cars, the combination with the draft members, draw-bar and draft yoke, of a stationary key between the draft members, front and rear stop members secured to the draft members, a compression resisting member extending in either direction beyond the key, and followers, the draft yoke being connected to the draw-bar and having a sliding engagement with the stationary key. 75
2. In a draft rigging for railway cars, in combination, draft members, a draw-bar, a yoke connected thereto, a stationary key, followers, a compression resisting member mounted between the followers, one of said followers being in front of the stationary key, and the other in the rear of the stationary key, the rear follower engaging the stationary key upon extreme forward movement of the draw-bar whereby the stationary key limits the forward movement of the rear follower. 90
3. In a draft rigging for railway cars, the combination with draft members, draw-bar, a draft yoke secured thereto, and stop members, of a stationary key mounted between the draft members, a compression resisting member, and followers, the draft yoke being provided with slots through which the stationary key passes, the rear follower being stopped against rearward movement by the rear stop members, and by the draft yoke through its said engagement with the stationary key. 100
4. In a draft rigging for railway cars, the combination with draft members, a draw-bar and a yoke connected thereto, of a stationary key mounted between the draft members, followers, compression resisting members between said followers and above and below the stationary key, the said followers being arranged on opposite sides of the stationary key. 110
5. In a draft rigging for railway cars, in combination, draft members, a draw-bar, a draft yoke connected thereto, stop members, followers, compression resisting members mounted between the followers, comprising upper and lower sets of springs, and means for supporting the compression resisting members, comprising a key passing between the sets of springs and secured at its ends in the draft members. 120
6. In a draft rigging for railway cars, in combination, draft members, a draw-bar, a yoke connected to the draw-bar, stop mem- 125

bers secured to the draft members, followers, upper and lower sets of springs between the followers, and a stationary key, the followers being provided with bosses about 5 which the ends of the springs are seated, the stationary key passing between the sets of springs and between the followers, the said

key being adapted to support the followers and springs.

JOHN F. O'CONNOR.
